UNITED STATES PATENT OFFICE.

WILLIAM S. WITTER, OF RIDOTT, ILLINOIS.

DUMPING END-GATE FOR WAGONS.

SPECIFICATION forming part of Letters Patent No. 625,006, dated May 16, 1899.

Application filed February 23, 1899. Serial No. 706,505. (No model.)

To all whom it may concern:

Be it known that I, WILLIAM S. WITTER, a citizen of the United States, residing at Ridott, in the county of Stephenson and State of Illinois, have invented certain new and useful Improvements in Dumping End-Gates for Wagons, of which the following is a specification.

The object of this invention is to produce a dumping end-gate that can be adapted to fit any wagon-box snugly enough to permit the hauling of small grain therein and that may also be used as a shoveling-board whenever desired.

15 Referring to the accompanying drawings, which form a part of this specification, Fig. 1 is a rear elevation of a wagon-box provided with my improvement. Fig. 2 is a top plan view of the parts shown in Fig. 1 with 20 the upper cross-piece and upper locking devices of the end-gate wanting. Fig. 3 is a side elevation of the parts shown in Fig. 1. Fig. 4 is a like view of the same with the end-gate thereof in position to allow the contents 25 of the wagon-box to be dumped thereout. Fig. 5 is also a like view of the same with the end-gate adjusted for use as a shoveling-board. Fig. 6 is a bottom plan view of the wagon end-gate. Fig. 7 is a detailed top plan 30 view of parts employed to connect the end-gate with the wagon-box and will be fully described hereinafter. Fig. 8 is a top plan view of fastening devices clearly shown in elevation in Fig. 1.

35 A A' are the sides and bottom of a wagon-box, the former of which is provided with the usual end-board cleats A², which are secured thereto, so as to form vertical end-board ways A³, Fig. 2.

40 B are rectangular strips of any desired thickness, each provided with a rectangular tongue B', preferably of light angle-iron of the form shown, Fig. 2, secured thereto and of suitable dimensions to be slid into the 45 ways A³, formed by the cleats A². The strips B are also secured to the wagon-box by means of bolts and nuts B² B³.

C are single-leaved strap-hinges provided with end-gate stops C' and locking-lugs C², 50 integral therewith, and pivoted at their lower ends to the inner faces of the strips B by means of pintles C³.

D is an end-gate, the component parts

whereof are secured together by means of the cross-pieces D' D², of suitable width to swing 55 vertically between the strips B, provided with side-boards E, secured thereto and adapted to be engaged by the stops C' when the end-gate is in a vertical position or in use as a shoveling-board and hinged at its upper portion to 60 the upper ends of the hinges C on pivot-pins D³, terminating at their outer ends in eyes D⁴.

F are retaining-pins to be inserted through the eyes D⁴ in the pivot-pins D³ into the vertical sockets F' in the upper ends of the strips 65 B to provide hinge-bearings for the end-gate D when it is desired to raise it preparatory to dumping a load from the wagon-box, Fig. 4.

G are locking-rods provided with eyes G' 70 G² at their outer and inner ends, by the former of which they connect with eyes H on the eyebolts H'.

I, Figs. 1 and 2, are straight-edged strips of metal secured to the outer face of the end-gate D to insure close durable joints between 75 the same and the strips B.

J J' are flat strips of metal secured to the end-gate D to furnish bearings and a fastening for parts to be described hereinafter, the inner end of the former curving downward, 80 outward, and upward to form a catch J² and the outer ends of both being bent inward through the rings K, which are of smaller internal diameter than the external diameter of the eyes G' on the locking-rods G, which 85 pass and freely slide therethrough.

L is a locking-rod fastening provided with transverse lugs L' L² to engage with the eyes G² on the locking-rods G, pivoted at L³ to the end-gate D and terminating at its free end in 90 a latch L⁴, adapted to engage the catch J², whereinto it may be secured by means of a pivoted button L⁵.

The parts G L, with their attachments and connections, constitute the upper locking devices of the end-gate D. 95

M are shanks terminating in transverse catches M', having holes M² extending therethrough and secured to the end-gate D.

N are screw-eyes projecting downward from 100 the under side of the cross-piece D².

O is a bell-crank having a short arm O' and a long arm O² and jointed at the center of the short arm O' to the under side of the cross-piece D² by means of the pivot-pin O³. 105

P are two rods—one pivotally connected

with the outer and the other with the inner end of the part O' and extending through the eyes N, the holes M² in the part M', and the hole Q in the part C².

5 R is a catch for locking the bell-crank O in the position clearly shown in Figs. 1 and 6.

The parts O P M', with their attachments and connections, constitute the lower locking devices of the end-gate D.

10 S is a handle for operating the end-gate D on the bearings, composed of the parts D⁴ F.

Figs. 1 and 4 show the wagon-box with the end-gate D locked in position to retain therein anything that it may be desired to carry there-
15 with.

If the locking-rod fastening L be disengaged from the catch J² and carried downward to the position indicated by dotted lines, Fig. 1, the inner ends of the locking-rods G may be
20 disengaged therefrom. Thereafter disengage the arm O² of the bell-crank O from the catch R and turn the same to the position indicated by dotted lines, Fig. 6. The rods P will be thereby withdrawn from engagement with

25 the parts C' M' and the end-gate may be raised to the position shown in Fig. 4 preparatory to dumping any desired load from the wagon-
box. If the end-gate D, Fig. 4, be now lowered to the position shown in Fig. 3 and the

bell-crank O and rods P be restored to the 30 positions shown in solid lines in Figs. 1 and 6 and the retaining-pins F be withdrawn from the sockets B' and eyes D⁴, the same may be lowered to the position shown in Fig. 5, where it is adapted to serve as a shoveling-board. 35

I claim—

1. In an end-gate for wagon-boxes, in combination, a wagon-box, an end-gate, a pair of strap-hinges pivoted, at their lower ends, to the inside of the lower portion of the wagon- 40 box, and, at their upper ends, to the upper portion of the end-gate, and the upper and lower locking devices of the end-gate, substantially as and for the purpose specified.

2. In an end-gate for wagon-boxes, in combination, a wagon-box, an end-gate, a pair of single-leaved strap-hinges, provided with end-gate stops and locking-lugs and pivoted, at their lower ends, to the inside of the wagon- 45 box, and, at their upper ends, to the upper portion of the end-gate, and the upper and lower end-gate locking devices, substantially as and for the purpose specified. 50

WILLIAM S. WITTER.
